UNITED STATES PATENT OFFICE.

SAMUEL MOANA KEKUEWA, OF LAHAINA, TERRITORY OF HAWAII.

PROPELLER.

1,290,573.

Specification of Letters Patent.

Patented Jan. 7, 1919.

Application filed December 23, 1916, Serial No. 138,560. Renewed June 6, 1918. Serial No. 238,581.

To all whom it may concern:

Be it known that I, SAMUEL M. KEKUEWA, residing at Lahaina, Maui, Territory of Hawaii, have invented certain new and useful Improvements in Propellers, of which the following is a specification.

This invention relates to certain new and useful improvements in propellers for water navigation or aerial navigation, and the invention particularly has for its object to provide an improved construction of propeller in which provision is made for obtaining a better "grip" on the fluid medium through which the vehicle is being propelled, than is done in the ordinary types of propellers now in common use, and the invention has for its object to provide a construction which can be adapted and used not only for the propulsion of vessels through water but may be used on air ships and aeroplanes.

In its generic nature, the invention comprises a duplex propeller composed of a front and a back set of blades, the rearward set of blades being offset with relation to the forward set of blades and being of a shorter spread than the forward blades, the two sets of blades being somewhat diverged from one another from the hub outwardly whereby the propeller blades will effect a double grip on the fluid medium, as it were, and thus prevent racing of the propeller.

In its more detail nature, the invention includes those novel features of construction, combination and arrangement of parts, all of which will be first fully described, then be specifically pointed out in the appended claims, and illustrated in the accompanying drawings, in which:—

40 Figure 1 is a rear elevation of one form of the improved propeller.

Fig. 2 is a side elevation.

Fig. 3 is a vertical longitudinal section on the line 3—3 of Fig. 1.

45 Fig. 4 is a rear elevation of a modification of the invention.

Fig. 5 is a side elevation of the form shown in Fig. 4.

Referring now to the accompanying drawings, in which like numerals of reference indicate like parts in all of the figures, 1 designates the shaft on which the propeller hub 2 is suitably mounted. Projecting from the hub 2 is a pair of master blades 3 which are inclined slightly from the vertical plane and 4 represents a subsidiary pair

of blades located in rear of the blades 3 and inclined from the vertical plane in a direction opposite to the inclination or curvature of the blades 3, it being understood that both blades 3 and 4 are pitched in the same general direction so as to effect a propulsive force in the same general direction.

It will be noticed that the blades 4 are of shorter length than the blades 3, as it is found that such a construction of propeller exerts a more uniform and non-slipping grip on the fluid medium than would otherwise be the case. It will be also noticed that the two sets of blades are offset with relation to one another, (see Fig. 1) to some extent, the blades, however, overlapping throughout a large part of their area, as is clearly shown in Fig. 1 of the drawings.

Instead of using one propeller of two sets of blades, such as shown in Figs. 1-3, inclusive, the units may be duplex, as shown in Figs. 4 and 5, for instance, in which event, one unit will be set at right angles to the other unit so as to give the appearance of a four-bladed propeller when viewed in end view, as indicated in Fig. 4.

It should be understood that the propeller may be made in any size desired, dependent upon the work it has to do. For aeroplane use, the blades are, of course, made considerably longer than for use in a fluid medium, such as water.

From the foregoing description taken in connection with the accompanying drawing, it is thought the complete construction, operation and advantages of the invention will be readily understood by those skilled in the art.

What I claim is:—

1. A propeller comprising a hub, two sets of blades mounted on said hub, one set being located directly in advance of the other set, and offset with relation thereto, one set of blades being curved in one direction and the other set of blades being curved in the opposite direction, both sets of blades having their pitch or inclination in the same general direction to each effect a propulsive force in the same general direction.

2. A propeller comprising a hub, two sets of blades mounted on said hub, one set being located directly in advance of the other set, and offset with relation thereto, one set of blades being of lesser length than the other, one set of blades being located in one direction and the other set of blades being curved

in the opposite direction, both sets of blades having their pitch or inclination in the same general direction to each effect a propulsive force in the same general direction.

5 3. In a propelling mechanism, a shaft, two propellers on said shaft, each propeller including a hub and two sets of blades, one set of blades being a major set and the other set of blades being a minor set, the minor 10 set being directly located to the rear of and

offset with relation to the major set, one propeller being mounted on the shaft in a position 90' from the position of the other set, one pair of blades of a propeller being curved in one direction with relation to the 15 vertical and the other pair being curved oppositely thereto, both sets being pitched in the same direction.

SAMUEL MOANA KEKUEWA.
